William & Pritchard

UNITED STATES PATENT OFFICE.

EDMUND R. BARANY, OF BROOKLYN, NEW YORK, ASSIGNOR TO FRANCO ELECTRIC CORPORATION, A CORPORATION OF NEW YORK.

FLASH LIGHT.

Application filed July 8, 1922. Serial No. 573,686.

To all whom it may concern:

Be it known that I, EDMUND R. BARANY, a citizen of the United States, and resident of the borough of Brooklyn, county of Kings, city and State of New York, have invented certain new and useful Improvements in Flash Lights, of which the following is a specification.

This invention relates generally to flashlight 10 lights but has particular reference to that class of such devices as employ one or more lamps at each end of the same adapted to be placed in circuit with a suitable source of electrical energy.

15 An important object of the invention is to provide, in a flashlight of the class mentioned, an improved means for supporting the lamps in an operative position with respect to the several associated elements, and 20 a novel means for controlling the circuits leading to said lamps from a suitable source of electrical energy.

Other objects and certain advantages of the invention will become apparent from 25 the following description when taken in connection with the accompanying drawings in which;

Figure 1 is a view in elevation of a flashlight embodying my invention.

30 Figure 2 is an end view of the flashlight shown in Figure 1.

Figure 3 is a sectional view taken on line 3—3 of Figure 1.

Figure 4 is a sectional view taken on line 35 4—4 of Figure 3.

Figure 5 is a sectional view taken on line 5—5 of Figure 3.

Figure 6 is a sectional view taken on line 40 6—6 of Figure 3.

In the drawings wherein is shown what I at present consider the preferred form of 45 my invention, the numeral 5 indicates an elongated casing, within which is arranged the usual form of cell 6, the carbon electrode 7 of which is disposed centrally within the customary zinc container 8 which forms the opposite electrode of the cell.

The cell 6 is provided with a cardboard or other insulating sleeve 9 which, as will be 50 readily understood, serves to insulate the cell from the casing 5. It will be understood that while I have shown the source

of electrical energy as consisting of a single cell, a plurality of cells may be employed and maintained in an end to end relation 55 within the casing 5, in accordance with usual practice.

Within the casing 5, at one end thereof, there is arranged an insulating disc 10, which is supported by insulating rings 11, seated upon a ledge 12 formed in the casing 5 by rolling the same to form a bead as shown at 13. This insulating disc carries a cup shaped metallic element 14 which is provided centrally with a screw threaded lamp support 15, into which is fitted the outer screw-threaded contact 16 of the usual form of lamp 17. Upon the cup shaped element 14 there is arranged an insulating disc 18 which is provided centrally with an opening 19 through which the central contact 20 of the lamp 17 projects. Upon the insulating disc 18 there is arranged a metallic disc 21 carrying a contact element 22 which is provided intermediate its ends with an arch 23 adapted to contact with the carbon electrode 7 of the cell 6. The insulating disc 10, the cup shaped member 11, the insulating disc 18, the metallic disc 21, and its associated contact element 22 are retained 75 in a unit by means of rivets 24, which are insulated from the cup shaped element 14 by reason of the provision of relatively large openings 25 formed therein. The casing 5 is screw threaded as shown at 26 and is 80 adapted to receive a screw threaded ring 27 which is provided at one end with a flange 28 adapted to engage the insulating disc 10 and retain the same in position upon the rings 11. In order that the screw 85 threaded ring 27 may be readily removed from the end of the casing 5 there is provided a pair of wings 29, formed integral with the flange 28, which enable one to readily unscrew the ring 27, as will be 90 appreciated. Upon the screw threaded portion 26 of the casing there is arranged a screw threaded reflector head 30 which carries a reflector 31 provided centrally with a relatively large opening 32 by the presence of which, insulation between the screw threaded contact 16 of the lamp and the reflector 31 is provided. Upon the outer end of the reflector

31 there is arranged the usual form of lens or closure 33. It will be readily appreciated that by turning the reflector head 30 in one direction or the other the position of the reflector 31 may be changed with respect to the lamp 17 in order to accomplish a focusing of the light rays emitted by the lamp 17 by which focusing the light beam may be concentrated upon a given area.

10 The opposite end of the casing 5 is screw threaded as shown at 34 and is adapted to receive thereupon a reflector head 35 which is screw threaded as shown at 36 and provided with an inturned flange 37. Upon the flange 37 there is positioned a reflector 38, the inner end of which is screw threaded as shown at 39 and adapted to receive the screw threaded outer contact 40 of an electric lamp 41. Upon the outer end of the reflector 38 there is disposed the usual form of lens or closure 42 which is retained in position by means of a lens ring 43 having screw threaded engagement with the screw threaded portion 34 of the reflector head 35.

15 Within the reflector head 35 there is arranged an insulating disc 44 which carries a metallic plate 45, struck up intermediate its ends to provide a contact 46 adapted to electrically engage the central contact 47 of the lamp 41. The insulating disc 44 also carries a metallic disc or ring 48, the periphery of which is adapted to contact with the head 35. The ring 48 is provided centrally with an annular flange 49 adapted to cooperate with a grooved ring 50 which carries a compression spring 51 adapted to contact with one end of the zinc container 8. Around the grooved ring 50 there is arranged an insulating ring 52 with which is associated a metallic ring 53. The plate 45, disc 44, rings 48, 52 and 53 are retained in an assembled relation by means of rivets 54 which are insulated from the ring 48 by reason of the provision therein of relatively large openings 55. In order to retain the several elements above referred to in their respective positions within the head 35, there is provided a locking ring 56 which is arranged within an annular groove 57 and adapted to engage the ring 48 at the periphery thereof.

20 To control the circuit through the lamp 41 there is provided a switch, indicated as a whole by the numeral 58. This switch comprises a slide 59 adapted to operate upon a switch box 60. The slide 59 is provided with wings 61 which extend inwardly through parallel slots 61' and so engage a safety cam 62 that the same is moved with the slide 59 in either direction. Between the switch box 60 and the casing 5 there is disposed an insulating plate 63 to which is attached a circuit closure 64 having contact arms 65 and 66. The circuit closure 64 is also provided with an arm 67 which carries a button 68 adapted to be depressed when the slide 59 is moved into engagement therewith and over the same. Within the casing 5 there is arranged a conductor strip 69, one end of which terminates below the arm 66 whereas the other end is passed through a guide 70 at one end of the casing and so held as to contact with the metal disc 53 when the head 35 is assembled upon the casing 5. Within the casing 5 there is arranged another conductor 71 which is electrically connected at one end to the contact element 22 and terminates at its other end directly beneath the contact arm 65. In order to close the circuit through the lamp 41, the slide 59 is so moved that the safety cam 62 contacts with the arm 65 and moves the same into engagement with the end of the conductor 71 whereupon one may depress the button 68 with his finger to move the arm 66 into engagement with the conductor 69 to close the circuit, or the button 68 may be depressed by further moving the slide 59, as will be readily understood. With the arms 65 and 66 electrically engaging the conductors 71 and 69 respectively, current will be transmitted from the carbon electrode 7 through the conductor 71, from which it passes through the closure 64 to the conductor 69 and thence to the contact 46, through the lamp 41 to the reflector 38, and back to the zinc electrode 8 by way of the disc 48 and the spring 51.

25 To control the circuit through the lamp 17 there is provided a switch 72 which is identical with that indicated by the numeral 58. Within the casing 5 there is arranged a conductor 73 one end of which terminates below the arm 66, of the latter named switch, whereas the other end of the conductor is adapted to electrically engage the metallic cup shaped member 14. When it is desired to close the circuit through the lamp 17, the switch 72 is operated in the same manner as switch 58. When the arm 65 is brought into engagement with the casing 5 and the arm 66 moved to electrically engage the conductor 73, current will flow from the carbon electrode 7 through the contact element 22 and disc 21 to the lamp 17 through the cup shaped element 14, the conductor 73, through the closure 64 to the casing 5, and back to the zinc electrode 8 through the disc 48 and spring 51.

30 From the construction of the device embodying my invention it is apparent that either one of the lamps may be placed in circuit independently of the other, or, if desired, both of the lamps may be made to function at the same time through the independent switches 58 and 72. It will be appreciated that by the provision of the arms 65 in both of the switches it is impossible to accidentally or otherwise close the circuits by depressing the buttons 68 without 130

first so moving the slides 59 as to bring the arms 65 into contact with the conductor 71 and the casing 5 respectively.

Having thus described my invention I claim:

1. A flashlight comprising a casing adapted to receive a battery, a lamp at one end of said casing, means for electrically connecting said lamp in circuit with said battery, a reflector head carried at the opposite end of said casing, a lamp associated with said head, an insulating member associated with said head, a contact associated with said insulating member, said contact being adapted to engage the second named lamp, a metallic member electrically connected with said head, said metallic member being insulated from said contact by said insulating member, means for maintaining said contact, said insulating member and said metallic member united in an assembled relation as a unitary structure, a spring electrically connecting said metallic member with said battery, said spring being adapted to engage one electrode of said battery and urge the other electrode of said battery toward the first mentioned lamp, and means for placing the second mentioned lamp in circuit with said battery through said metallic member and spring.
2. A flashlight comprising a casing, a lamp mounted at one end of said casing, a battery within said casing, means for electrically connecting said lamp in circuit with said battery, a reflector head carried at the opposite end of said casing, a reflector associated with said head, a lamp associated with said reflector, an insulating support associated with said head, a contact element supported by said support and adapted to engage the second named lamp, a spring associated with said insulating support and electrically connecting said contact element with one electrode of said battery through the second named lamp, said spring being utilized to urge the other electrode of said battery toward the first mentioned lamp, means embracing said spring for retaining the same in a fixed relation with respect to said insulating support, means for retaining said spring, said insulating support and said contact element in an assembled relation as a unitary structure and means for placing the second named lamp in circuit with said battery independently of the first mentioned lamp.
3. A flashlight comprising a casing adapted to receive a battery, a reflector head carried at one end of said casing, a reflector associated with said head, an electric lamp associated with said reflector, said lamp being provided with a pair of terminals, an insulating support associated with said head, a metallic member supported by said insulating support and adapted to engage one electrode of said battery, a contact element supported by said insulating member and electrically connected to said metallic member, said contact element being adapted to engage one terminal of said lamp, a second metallic element associated with said insulating support and adapted to engage the other electrode of said lamp, means for insulating said metallic member and said contact member from said second metallic member, means for retaining said metallic member, said contact member, said second metallic member and said insulating support in an assembled relation as a unitary structure, a spring adapted to engage one electrode of said battery and urge the other electrode thereof into intimate engagement with the first mentioned metallic member, a second lamp associated with said casing, and means for placing the first mentioned lamp independently of the second mentioned lamp in circuit with said battery through said metallic member, said contact member, the second named metallic member and said spring.
4. A flashlight comprising a conducting casing adapted to receive therein a battery, lamps arranged at opposite ends of said casing, conductors insulated from said casing and leading from one electrode of said battery through one lamp to the other electrode of said battery, means cooperating with said conductors for placing one lamp in circuit with said battery, and means including said casing for placing the other lamp in circuit with said battery.
5. A flashlight comprising a conducting casing adapted to receive a battery, electric lamps arranged at opposite ends of said casing, conductors insulated from said casing leading from one electrode of said battery through one of said lamps to the other electrode of said battery, a circuit closer adapted to establish and sever electrical communication between said conductors, and a second circuit closer adapted to establish electrical connection between opposite electrodes of said battery through said casing and the other of said lamps.
6. A flashlight comprising a conducting casing adapted to receive therein a battery, lamps arranged at opposite ends of said casing, conductors insulated from said casing and leading from one electrode of said battery through one lamp to the other electrode of said battery, means cooperating with said conductors for placing one lamp in circuit with said battery, and means including said casing for placing the other lamp in circuit with said battery, and means located at one end of said casing for exerting a thrust upon said battery in the direction of the lamp located at the opposite end of said casing.
7. A flashlight comprising a conducting casing adapted to receive therein a battery,

- lamps arranged at opposite ends of said casing, conductors insulated from said casing and leading from one electrode of said battery through one lamp to the other electrode 5 of said battery, means cooperating with said conductors for placing one lamp in circuit with said battery, means including said casing for placing the other lamp in circuit with said battery, and means constituting a 10 part of the circuit common to both circuit closers for urging said battery in a given direction within said casing.
8. A flashlight comprising a conducting casing adapted to receive therein a battery, 15 lamps arranged at opposite ends of said casing, conductors insulated from said casing and leading from one electrode of said battery through one lamp to the other electrode of said battery, means cooperating with said 20 conductors for placing one lamp in circuit with said battery, means including said casing for placing the other lamp in circuit with said battery, and means constituting a part of the circuit common to both circuit 25 closers for urging said battery in a given direction within said casing, said means being in the form of a spring electrically engaging one electrode of said battery.
9. A flashlight comprising a casing having a battery therein, a reflector head at one end of said casing, a lamp associated with said head, an insulating support, a contact element and a metallic member associated with said head and physically united in a 35 unitary structure, said contact element being electrically connected with said lamp and insulated from said metallic member by said support, a second lamp arranged at the opposite end of said casing and electrically connected to one electrode of said battery, means for electrically connecting the electrodes of said battery through said contact element, first mentioned lamp and metallic member, and means for connecting the electrodes of said battery through the second 40 named lamp and said metallic member.
10. A flashlight comprising a casing having a battery therein, a reflector head at one end of said casing, a lamp associated with said head, an insulating support, a contact element and a metallic member associated with said head and physically united in a unitary structure, said contact element being electrically connected with said lamp and 45 insulated from said metallic member by said support, a second lamp arranged at the opposite end of said casing and electrically connected to one electrode of said battery, means for electrically connecting the electrodes of said battery through said contact element, first mentioned lamp and metallic 50 member, and means for connecting the electrodes of said battery through the second named lamp and said metallic member.

member, means for connecting the electrodes of said battery through the second named lamp and said metallic member, and a thrust element electrically connected with one electrode of said battery and adapted to urge said battery in a given direction within said casing, said thrust element being common to the circuits of both of said lamps. 65

11. A flashlight comprising a conducting casing having a battery disposed therein, a reflector head at one end of said casing, an electric lamp associated with said head, a contact element, an insulating support and a metallic member associated with said head and physically united in a unitary structure, 70 said contact element being electrically connected with said lamp, and insulated from said metallic member by said support, a lamp arranged at the opposite end of said casing, one contact of said lamp being electrically connected to one electrode of said battery, the other contact of said lamp being adapted to be electrically connected with said casing, means for placing the electrodes of said battery in circuit with the first mentioned lamp through said contact element and metallic member, and means for placing the electrodes of said battery in circuit with the second named lamp through said casing 75 and metallic member. 80

12. A flashlight comprising a conducting casing having a battery disposed therein, a reflector head at one end of said casing, an electric lamp associated with said head, a contact element, an insulating support, and a metallic member associated with said head and physically united in a unitary structure, 85 said contact element and metallic member being electrically connected with said lamp and insulated from said metallic member by said support, a lamp arranged at the opposite end of said casing, one contact of said lamp being electrically connected to one electrode of said battery, the other contact of said lamp being adapted to be electrically connected with said casing, means for placing the electrodes of said battery in circuit with the first mentioned lamp through said contact element and metallic member, means for placing the electrodes of said battery in circuit with the second named lamp through said casing and metallic member, and a thrust element electrically connected with one electrode of said battery and arranged 90 in proximity to the first mentioned lamp for urging said battery toward the second named lamp, said thrust element being a conductor common to the circuits of both of said lamps. 100

In testimony whereof, I have affixed my 105 signature to this specification.

EDMUND R. BARANY.
